TELEVISION

Aloysius J. Cawley, Pittston, Pa.

Application February 3, 1930, Serial No. 425,610

5 Claims. (Cl. 178—6)

The invention relates to improved methods of transmitting visual images of objects or pictures from one point to another by means of wireless or wire. Some of the objects of the invention 5 are as follows:

The provision of a plurality of concentric cylinders in contradistinction to disks for producing the image. One of those cylinders may be a mask to obscure the undesirable intersecting 10 points of the light permeable areas carried on the other two cylinders. Or the third cylinder may carry means for concentrating the light along the path of the intersections produced by the light permeable areas of the other two cylinders.

Improved means is provided for rotating two or more cylinders in opposite directions.

Improved means for framing the pictures are disclosed, particularly with the object in view of 20 taking advantage of superposed projection of images. Also, a method of framing is provided wherein two intersecting points producing the scanning point traverse or scan the image field alternately. Also a method of scanning where- 25 in stereoscopic pictures are produced which may also be colored, one modification using two wave sources, another using one wave train with a plurality of circuits containing the photoelectric elements. A method of framing is also disclosed 30 which obscures the superfluous light dots and eliminates the rotating mask.

An improved method of scanning is disclosed that cuts the picture up into a series of dots rather than into a series of parallel dashes or lines 35 as ordinarily used. This possesses the very desirable characteristic of chopping the carrier wave into a series of waves all of which are of the same number. That is, the picture is built up of a large number of trains of radio frequency, 40 each train possessing exactly the same number of waves. The light and shade of the picture is produced by the variation of intensity of those wave trains, and this is their only point of difference, as their frequency is unaltered. This is 45 in sharp contrast to the variations produced in the ordinary scanned line of a television picture.

Images are transmitted that may be of a much greater width than height and thus more nearly approach the usual proportions of a theatrical 50 stage. A method of rotating the cylinders horizontally is also disclosed, in which this broader than wide picture is obtained.

A projection process is disclosed which employs two or more projecting means placed at different angles to the screen, while the screen is

provided with a series of ridges whereby the light from each projector is projected upon a certain series of surfaces of the ridges. That is, the right hand projecting means projects the picture on the right handed surfaces, while the left hand projector projects the light on the left hand surfaces. This gives three dimensional effects to the screen.

A method of producing pictures by means of only two concentric cylinders is shown. In- 10 stead of those cylinders having their light permeable areas in the form of openings made in opaque media, an arrangement is disclosed in which they consist of a number of cylindrical lenses, one series of lenses carried on one rotat- 15 ing medium concentrates the light into a line placed at a certain angle while the other cyl- 20 inder carries a series of cylindrical lenses that concentrates the light into a line that is at an angle to the lines produced by the other series 25 of lenses. The two series coact to concentrate all of the available light into a bright spot, thus giving a very bright image.

A method is also shown whereby the scanning dot is produced by two concentric cylinders, while 25 a disk at an angle thereto carries either masking areas to obscure undesirable light intersecting points, or a series of cylindrical lenses to concentrate the light into a bright line along the path 30 of the scanning dots or dashes.

A method of giving great strength and rigidity to the rotating cylinders which permits their light permeable surfaces to be in the closest pos- 35 sible contact. This causes the cylinders to be held in their exact geometric position. Contact 40 wheels also act to hold the peripheral portions of the cylinders in apposition, thus avoiding ext- 45 inishment of the intersecting scanning point.

A method of scanning in which oblong intersecting scanning bands are used, two of which 40 alternately scan a square field. Two dash scan- 45 ning may be used instead of the oblong light point also with this system.

The production of rectilinear pictures in con- 45 tradistinction to segmental pictures, such as those produced on a disk, etc.

To provide a system of "dot" or "mosaic" scan- 50 ning, although the visual image is evenly illumin- 55 ated, exposing only one dot or small area at a time.

Referring to the accompanying drawings form- 55 ing part of this specification, in which like refer- 60 ence characters have similar meanings in all of the views,

Figure 1 is an elevational view of a scanning

apparatus which employs three concentric cylinders, two of which produce the intersecting light point which scans the picture, while the third acts either as a mask to hide the undesirable light points, or to concentrate the light away from the undesirable light point path and upon the desirable light point paths. Multiple aperture frames are shown with this apparatus.

Figure 1a shows a framing method which employs a frame which is literally a frame shown in Figure 1 cut into two halves, separate light sources and lenses being provided for either half. This produces two distinct pictures, which are scanned by two light points acting alternately. Those pictures may be superposedly projected both as regards right and left and from top to bottom.

Figure 1b shows the three rotating media used in one of the modifications of Figure 1. Two oppositely rotating cylinders produce the scanning point while the third rotating element consists of a series of cylindrical lenses which concentrate the light along the path of the scanning light dots.

Figure 1c shows the cylindrical lens of Figure 1b concentrating the light in a path of the scanning light dots produced by two oppositely moving media. The picture is here shown as being scanned in dots.

Figure 2 is a side view of the device shown in Figure 1.

Figure 2a is a sectional view of Figure 2, taken on a plane slightly to the left of the vertical axis of Figure 2.

Figure 3 shows an elevational view of two concentric scanning cylinders and a very simple means for rotating them. There is no third element, a stationary mask being provided which eliminates the undesired scanning points.

Figure 3a shows a modification of the two cylinders shown in Figure 3, which consists of a series of cylindrical lenses each carried on one of two concentric cylinders. These act to concentrate all of the light into a travelling light dot.

Figure 3b shows that the rotating cylinders may have a blank portion thereon when used with such apparatus as that of Figure 1a. Or if but one series of images are to be produced with the apparatus of Figure 1a then the lower portion of Figure 1b may be taken advantage of for a cylinder surface.

Figure 3c shows a plan view of two concentric, oppositely rotating cylinders producing the travelling scanning point, while a disk rotating at right angles thereto provides either a mask or cylindrical lenses for concentrating the light along the path of the scanning points.

Fig. 3d is an elevation of a portion of the face of disc M1.

Figure 4 is a side view in elevation of the mechanism for rotating the two concentric cylinders of Figure 3.

Figure 5 is an elevational view partly in cross section showing how the ends of the cylinders may be separated for the purpose of inserting reinforcing means, while the periphery of the cylinders which bear the light permeable areas are very close together.

Figure 6 illustrates a method of holding the two peripheral portions of the rotating cylinders in exact relation in order that the light passing through the scanning points may not be interrupted, due to lateral vibration of one or the other rotating cylinder. This figure as well as

Figure 5 also discloses rims placed on the periphery of the cylinders in order to insure steady motion.

Figure 7 shows a method of scanning a square frame which utilizes two scanning points which alternately scan the picture area. The light permeable portions are shown in the form of two lines.

Figure 7a is a modification of Figure 7 in which dot scanning is used instead of the lines of Figure 7, each dot consists of a small rectangle which is twice as broad as high.

Figure 1 is a view of a television apparatus which may be used at the transmitting or receiving station, the only difference being that at the transmitting station a photoelectric cell is used, while at the receiving station a neon lamp or other electro-optical element is used. As the function of the apparatus herein is principally that of scanning, it is deemed unnecessary to complicate the already too long specification by showing it in relation to the transmitting and receiving antennae and associated circuits. It is well known that television may be produced by the alterations in brightness of a neon or other lamp which is in turn produced by the photoelectric alterations in a cell at the transmitting station in accordance with an image. The figure shows three concentrically mounted cylinders, two of which A and B rotate in opposite directions at nearly equal speed, while the third acts to eliminate the operation of undesirable light points produced by the intersecting light permeable areas of cylinders A and B, only the light points being permitted to function that are desired. The third cylinder M acts to either mask the undesired light points or to concentrate all of the light upon the path of desired light points.

Shaft 2 is mounted upon suitable supports, such as those shown. Wheels 1, 3 and 9, as is also cylinder A, are mounted rigidly upon shaft 2. Cylinders B and M are loosely mounted upon shaft 2. Wheel 7 is loosely mounted on shaft 2 also, and is attached to cylinder B, and rotates therewith. Wheel 13 is also loosely mounted on shaft 2 and is attached rigidly to the cylinder M. Stops 14 and 15 are rigidly attached to shaft 2 and act to hold wheels 7 and 13 in exact position as they are rotated. Power is applied to wheel 1 in any manner desired, such as by connecting a motor directly thereto, or by the use of a friction wheel W, sliding along the radius of the wheel to produce varying speeds. Shaft 2 turns wheel 3 which turns wheel 4. The wheel 4 is mounted upon the same shaft with wheel 6 which it turns. Wheel 6 turns wheel 7 and consequently cylinder B. Thus it will be seen that cylinders A and B rotate in opposite directions, cylinder A rotating with shaft 2. Wheels 4 and 6 are not of the same diameter, their difference in diameter being such that there is a difference in speeds between cylinders A and B that is in general equal to the number of pictures to be transmitted per second multiplied by the width of a picture. Different sized wheels 3 and 4 which are interchangeable may be used to produce any variation in the relative speeds of the two cylinders desired. Or 3 may be in the form of a sliding friction wheel (similar to W) which slides along 6 along its radius to produce any variation in speed desired. The relative speeds of the two cylinders just described causes the light permeable series a to intersect with the light permeable series b to produce an intersecting light dot, or scanning point in each of the image areas

of the frame *f*. Those dots are indicated by *i*. 5 indicates the photoelectric element which is a photoelectric cell at the transmitting station and a neon or other lamp at the receiving station. The lens or optical elements for each of the image areas are indicated by *l*. If the modification of the scanning method illustrated in Figure 1a is used, no third cylinder *M* is necessary. However, with the frame shown in Figure 1 a 10 third element is used. Wheel 9 is rigidly attached to shaft 2, and meshes with and turns wheel 8 mounted on the same shaft with wheel 10 which is also turned thereby. Wheel 10 turns wheel 11 mounted on the same shaft with wheel 12 which it turns. Wheel 12 meshes with and turns wheel 13. Wheel 13 turns freely on shaft 2 and is rigidly attached to cylinder *M*, also loosely mounted on shaft 2 and which is turned thereby. It will be noted that cylinder *M*, due to the great reduction in the gearing used, travels at a rate of speed that is much slower than that of either cylinder *A* or *B*. This speed should be equal to the number of pictures to be transmitted per second multiplied by the width of a picture. 15 In other words the masking areas *m* are turned at the same rate of speed as the rate of gain in speed of cylinder *A* over cylinder *B*. Thus, as a scanning dot traverses a picture, due to the excess of speed of *A* over *B*, the cylinder *M* moves 20 at such a speed as to continually provide a clear space for the scanning dot *i* while obscuring the superfluous dots. The frame *f* is shown in this figure as having three image areas. The images from those areas may be superposed as desired by projection.

If the frame which cooperates with three vertically disposed single images shown in Figure 1 is divided into twice as many areas by a vertical partition, we have the frame shown in Figure 1a. A separate photoelectric element is provided for each area, whether three are used as in Figure 1, or 6 are used as in Figure 1a. In the latter figure a frame is shown which consists of three pairs of image apertures placed one above the other. It will be noted that the right vertical three image areas are in phase, while the left three image areas are in phase, but differ from the right. Either the right three or the left three image areas may be superposed as shown 45 in Figure 2 upon screen *Sc*. As stated above, the right three produce an image that is different from the left three. Consequently, two carrier waves may be utilized, one of the right three and the other for the left three, suitable tuning means 50 limiting the particular wave to its particular group of photoelectric elements. Each image space is provided for the right three and another for the left three areas. Any desirable shading means such as *fl* may be used on frame *f*. 55 The two image areas in two series *a* and *b* are shown and have the same significance as in Figure 1. Referring to the lower portion of Figure 1a it will be noted that intersecting point *i* has just scanned space *S*, while *i'* is about to scan it. In space *r* light dot *i'* has just scanned, and the equivalent of light dot *i* is about to scan this picture entering from the right.

It is to be noted that the arrangement of the light permeable areas *a* and *b* in Figure 1a is 60 equivalent to that obtained by eliminating the zig zag line of light permeable areas shown in Figure 1, say that commencing at the upper left hand corner and proceeding thence to the upper right hand corner of the second image area

in frame *f* and thence to the left and down, etc., and by further breaking the partition between two consecutive or adjacent image areas, making the image area oblong, being twice as high as it is broad. In Figure 1a, obviously the same 5 scanning dot scans consecutively the right and then the left image area. It is to be noted in the scanning arrangement of Figure 1a that the number of scanning lines is not altered in any way, but their length is cut in half, and this is 10 of much less importance than cutting down their number would be, as any particular scanning line varies its intensity with more or less continuity. Not much of the image producing property is lost. If any is lost, this may be 15 compensated for by providing cylindrical lenses *lc* which act to make the picture either square or nearly so. However, their use may be rendered unnecessary by turning the scanning apparatus on its side and placing the cylinders in 20 a horizontal position as shown in Figure 2, in this way the picture would be viewed as a rectangle that would be twice as wide as it is high, and thus more nearly approximate the proportions of the average theatre stage. The spherical lenses are 25 shown at *l* for viewing or projecting the image upon a screeen, either as shown in Figure 2 as upon *Sc* with its ridges for producing stereoscopic effects indicated by 23. A color screen may be placed in front of each of the left vertical 30 three image spaces, and may consist of red orange, while another screen such as blue violet may be placed in front of the right vertical three spaces. These may be superposed in the manner described or otherwise viewed directly to 35 give color effects, as the left three and the right three produce different images.

Figure 1b shows an arrangement in which cylinder *M* is provided with a series of cylindrical lens *lc* whose axes are placed in a horizontal 40 position. As the cylinder rotates, the light is concentrated in a bright line or band along the course of the scanning points shown at *ic* of Figure 1c. *A* and *B* rotate in opposite directions as described, while the intersecting portions of 45 the light permeable areas cause a scanning of the image area by light points as shown by the dotted lines passing through the opening in the cylinders *A* and *B* and indicated by *i*. The light passes to the photoelectric element at the transmitter and from the electro-optical element (neon tube) at the receiver. Thus the undesirable light points will be eliminated, due to the fact that they are deprived of light, all of the light being concentrated in the path of the desirable light points *i*.

Figure 1c shows a side view of Figure 1b, which is really a face view of the cylinder carrying the cylindrical lenses *lc*. Through this may be seen the desirable intersecting light point *i*, and its 60 scanning path is indicated by *ic*. Point *i* is at the center of its scanning path. *a* and *b* are here shown as squares, and it is to be particularly noted that the scanning consists in opening successive squares along the light path *ic*. Only 65 one square is opened at a time, the next square does not start to open until the one which has just been opened is fully closed. The picture is scanned by isolated squares, i. e., they are isolated in the point of time only (chronologically). 70 They are however placed immediately in contact with each other, so that there is no space between adjacent squares. A chopper effect is produced, but the viewed scanned picture is perfectly homogeneous, as though made up of uninter- 75

rupted light. This method of scanning the picture in squares or other very small portions has the advantage over the usual method of scanning the picture in lines, and the line is interrupted with different frequencies, thus disturbing the radiated frequency of the waves. This acts to set up a series of broadcasted waves that differ greatly from one another from instant to instant and over almost all of the frequencies used in broadcasting, thus constituting the one great drawback in television. That is, many different frequencies of radio frequency are produced in the waves emanating from the transmitting station, making it almost impossible to confine the picture to its intended broadcast frequency. This difficulty does not exist in sound broadcasting, as the sound waves can only vary the carrier wave within the frequency limits of audio frequency. This difficulty in transmitting television images is overcome by the method of scanning i. e. the type of scanning media shown in Figure 1c and Figure 7a of this application. This method was also disclosed in my application Serial Number 391,541, filed September 10, 1929 for Scanning process, being disclosed in connection with Figure 8 of that application, and the present application is made a continuation in part of that application. By this method of scanning, it will be noted that the picture is dissected virtually into fine squares, rectangles or circles, as the invention covers them all. Instead of the scanning path *ic* of Figure 1c being a long band, it is in reality a series of closely juxtaposed squares with no dark interval between them. Therefore, in the case of ordinary scanning the carrier wave is subjected to the uninterrupted influence of the band. However as this band traverses the image area and encounters the different degrees of light and shade, the carrier wave is altered into almost every possible frequency, which causes great interference to other broadcasting. In the type of scanning illustrated in Figure 1c, each scanned line such as *ic* is broken up into a number of minute squares, circles, rectangles, etc. The carrier wave, in turn is chopped up into a large number of sections or trains, each train having exactly the same number of waves. Those trains differ from each other only in intensity. That is the wave trains differ from each other only in the amplitude of vibration of the waves which constitute those wave trains. There is no difference in the frequency or in the wave length of the waves constituting the various wave trains. Consequently there is no interference in broadcasting on other wave lengths than that of the broadcast carrier wave of the television transmitter. This highly desirable feature of broadcasting television is also comprised in the method of scanning disclosed in my application Serial Number 380,202, filed July 22, 1929, entitled Television apparatus. In that application, the picture was scanned also in virtual dots, instead of in dashes, as at present employed. This application is also a continuation in part of that application as regards the method of breaking up the carrier wave into a number of units each of which are identical except for the variation in intensity, or in other words, except for the variation in amplitude of the waves constituting the wave trains. Figure 1c shows an image area of a frame *f*. This process of breaking up the carrier wave into a number of identical frequency units is considered very important.

Figure 2 is a side view of the apparatus of Fig-

ure 1. It also discloses the fact that the cylinders, whether two or three may be placed in a horizontal position. This is very desirous if the type of image aperture shown in Figure 1a, such as that at *S*, is used. If no cylindrical lens is used with *S*, the picture would then be twice as wide as high, thus more nearly approaching the proportions of stage theatres. Disks *A*, *B* and *M* have the same significance as in Figure 1. Disk *M* may be dispensed with in certain types of scanning, such as that of Figures 1a, 8b, etc. three apertures are shown in frame *f* attached to support and frame and housing 32, which also carries the photoelectric elements 5, one being provided for each image area or aperture. Support 32 is carried on movable arm 31, which is in turn pivoted on shaft 2. 33 is merely a rest for the movable frame *f* and support 32. This aids in bringing the pictures into frame. The optical system for projecting the picture is shown at 20 7; there are three of them, one for each image. Those pictures are shown as being superposed upon the screen *Sc*, which may or may not be provided with ridges 23. The figure shows a frame of three apertures as shown in Figure 1. 25 However, the right or left three apertures of Figure 1a may be superposedly projected. Or, all six apertures of Figure 1a may be superposed into one image by projection. That is each three vertical areas may be superposed by vertical 30 movement or focussing, and both of the resulting images may be superposed by lateral focussing. This is further illustrated in Figure 6.

Figure 2a shows a more detailed view of the framing, carrying and housing features of the 35 apparatus. 31 is a movable arm which supports the frame *f* and housing 32 carrying photoelectric element (cell or lamp) 5. The cylinders *A* and *B* are shown, also cylinder *M* which may or may not be used.

Figure 3 is an elevational view of two concentric scanning cylinders, showing a very simple mechanism for moving them in opposite directions, also showing a means of shortening the bearings by supporting on a table like structure 45 and permitting the cylinders to overhang the edge. There are only three gear wheels in this modification. Surfaces *A* and *B* cause light permeable areas *a* and *b* to intersect, producing the light points *i*. A stationary frame *f* is 50 shown which obscures the undesirable intersecting points *i'* and permits points *i* to function. The image area is half as high as wide, approaching the dimensions of a theatre stage.

Figure 3a shows a modification of the moving 55 media. Here the cylinders *A''* and *B'* are shown as carrying cylindrical lenses *a'* and *b'*. The lines indicate the axes of the cylindrical lenses. *A''* and *B'* move in opposite directions as by the mechanism shown in Figure 3. The lenses 60 concentrate all of the light impinging upon the image area into a bright point which scans the picture in horizontal lines. This has the advantage of adding great brilliancy to the picture.

Figure 3b shows another modification of the 65 scanning media. Here *A'* is shown at the upper portion as having the left hand portion blank to obscure the left hand side of Figure 1a. The lower portion shows that it may be cut off at the center, leaving only a scanning medium 70 over the right hand portion of Figure 1a. It is to be here noted that the arrangement of scanning shown in Figure 1 may be altered by cutting out the partition between adjacent scanning areas of frame *f*, thus making the image area oblong 75

instead of square. By omitting the chain of light permeable areas *a* and *b* commencing at the upper left hand portion and passing thence to the lower right hand portion of the upper square and thence to the left, thence to the right, and so on, a scanning arrangement is obtained that is similar to the right hand portion of Figure 1a or of that shown in Figure 3b.

Figure 3c is a plan view of an apparatus using two scanning cylinders A and B that rotate in opposite directions. The mechanism is the same as that of Figure 3, with the addition of a few elements. In both Figure 3 and 3c wheels 1 and 3 and disk B are firmly attached to the shaft, while wheel 7 and disk A move freely on the shaft and are attached to each other. Power moves wheel 1, shaft 2, wheel 3 and cylinder A in one direction. Wheel 3 moves wheel 4 and the latter moves wheel 7 together with cylinder B. The gear surface of wheel 4 is made broad so that wheel 7 meshes with it at the periphery, while wheel 3 meshes with it nearer the center. This causes A to have a faster speed than B and produces the scanning progression, or the shifting of the scanned line. In addition to Figure 3, the apparatus shown in Figure 3c comprises a wheel 34 placed on the same shaft with and moved by wheel 4. Wheel 34 meshes with wheel 35 mounted on the same shaft as disk M. Thus disk M is turned at a much slower rate than either A or B. 5 indicates the photoelectric element. Cylinders A and B produce the scanning light dot *i*, as described in connection with Figures 1 and 3, while the disk M may carry either a mask *m*, as shown in Figure 3d to cover undesirable light intersecting points, or a series of cylindrical lenses as shown in Figure 1b at 1c.

Figure 3d is a sectional elevation view of the face of the disk M. It shows a three image area frame *f* with their three pairs of intersecting light permeable areas *a* and *b*, with areas *m* masking the undesirable intersecting light points.

Figure 4 is a side view of Figure 3, showing the simplicity of the mechanism. Shaft 2 carries wheel 3, which meshes with wheel 4, carried on shaft 2a. This is merely to augment Figure 3 as far as illustration is concerned.

Figure 5 is intended to illustrate the fact that great rigidity may be given to the concentric cylinders, while permitting their surfaces to come into close apposition without touching. This is due to the fact that there may be great separation of the ends of the cylinders A and B, thus permitting the use of elaborate reinforcing disks, etc., while their surfaces carrying the light permeable areas may be in close apposition. This insures accuracy of scanning. Means for reducing the friction are also illustrated. Rims 22 are shown as attached to the cylinders in order to assist in giving symmetrical motion thereto, i. e., to insure steadiness and eliminate vibration. Cylinder A is shown rigidly attached to the shaft 2, on either side of it are placed the large reinforcing disks 16 to give rigidity to the cylinder. Cylinder B is shown mounted on ball bearings, the central portion being shown at 17 and as being rigidly attached to the shaft. The balls are shown at 20a. The cylinder B is fixed between the moving elements in the ball bearing structure. Those moving elements are shown at 19. Gear wheel 7 is rigidly attached through a spacing element to the movable portion 19, and thus moves rigidly with cylinder B. A ball bearing is shown between movable element 19 and 16 at 20. It will be seen that the cylindrical surfaces

21 are in the closest possible apposition, as they are independent of the distances between cylinder ends.

Figure 6 shows a means intended to prevent lateral vibration of the moving cylinders A and B. 5 are two wheels, one of which bears against the end of cylinder A, while the other bears against the rim 22 attached to cylinder B. Wheels 26 are of large diameter and of little friction. 27 is the casing of the apparatus, showing the viewing aperture.

Figure 7 illustrates another method of scanning a picture which employs two alternately scanning light points *i* and *i'*. Media A and B carry light permeable bands *a* and *b*. The image area in 15 the frame *f* is here square. The dotted lines show the relation of the scanning lines to the visual area. A diagonal line runs from the upper right hand corner to the left middle portion of the side of the square, while another runs from here to the lower right hand corner. *a* and *b* should have this length and inclination, *a* and *b* are shown displaced from this dotted line in order to illustrate the fact that *i* has just scanned as indicated by the dotted tail of an arrow, while *i'* is just entering the visual field, and is about to scan the line indicated by the dotted arrow head. Obviously a visual image area may be scanned that is wider than it is high by drawing lines similar to the instructions given in connection 30 with the description of the broken lines, and arranging the light permeable areas accordingly.

Figure 7a shows a modification of the scanning arrangement illustrated in Figure 8. Here instead of the uninterrupted bands, we have *a* made 35 up of a series of steps of rectangular openings, while *b* is also made up of a similar series of openings. This will produce the same type of scanning as described in connection with Figure 1c, the difference being that here the dots consist 40 of rectangles rather than squares. Only one point is illuminated at a time. The next rectangle starts to admit light just as soon as the previously illuminated rectangle is completely closed. Thus, we have a series of wave trains 45 sent out by the transmitting station and received by the receiving station, each train being identical with its fellows as regards frequency and wave length of the waves constituting the wave train, the only difference being in amplitude of vibration 50 of the waves. And it is this variation in amplitude that produces the picture, furnishing the lights and shade.

It is to be understood that the apparatus is very flexible. For instance, the journal caps in Figures 1 and 3 may be lifted off after loosening the necessary bolts and disk M together with any of its gear wheels removed. The caps are replaced and this leaves the apparatus consisting of only two cylinders.

Having described my invention, I claim as new and desire to secure by Letters Patent:

1. A television apparatus consisting of three concentrically mounted cylinders, the cylindrical surfaces of said cylinders overlapping and their 65 bases adjacent, light permeable areas carried on two of the cylindrical surfaces of said cylinders which intersect to form transversely moving light points, a frame associated with said cylindrical surfaces in which said light points move, light 70 masking areas carried on the third of said cylindrical surfaces which act to obscure all but one of said light points in said image area at any instant.

2. A television apparatus consisting of three 75

concentrically mounted cylinders, a motor connected through suitable gearing to differentially move said cylinders, the bases of said cylinders being adjacent and their cylindrical surfaces overlapping, an image frame in cooperative relation with said cylindrical surfaces, light permeable areas on two of said oppositely moving cylindrical surfaces which intersect to form transversely moving light points in said frame, the third of said cylindrical surfaces carrying a series of cylindrical lenses which concentrate the light in the path of but one light point in said image area at a time.

3. A television apparatus consisting of three differentially moving, concentrically mounted cylinders, the bases of said cylinders being adjacent and the cylindrical surfaces of said cylinders overlapping, light permeable areas carried on two of said cylindrical surfaces which intersect to form moving light points to control the passage of light through the plane of said surfaces, a frame in relation to said surfaces in which said light points move, light masking areas carried on the cylindrical surface of the third of said cylinders surfaces which act to limit the number of said light points to one in said image frame, suita-

ble gearing for differentially moving said cylinders and a photoelectric element in relation with said frame.

4. A television apparatus consisting of two oppositely moving media, suitable gearing operatively connected with said media, light permeable areas carried on said moving media which intersect to form scanning light points, a frame in which a single image is formed and in which said light points move, two distinct apertures in said frame in each of which but one light point moves and a photoelectric element cooperating with each of said apertures.

5. A television receiver consisting of a plurality of image varied light sources, a frame adjacent said light sources, two distinct apertures formed in said frame each of which cooperate with one of said light sources to form a single image in said frame, two oppositely moving, overlapping media located between said light sources and said frame, light permeable areas carried on said moving media which intersect to form scanning light points, but one of said points moving in each of said apertures at a time to form a single image.

25

ALOYSIUS J. CAWLEY.
